Inventor: by his attorney.
 Frederick Curtis,

United States Patent Office.

HENRY O. LOTHROP, OF MILFORD, MASSACHUSETTS.

Letters Patent No. 77,989, dated May 19, 1868.

IMPROVEMENT IN STEAM-ENGINES.

The Schedule referred to in these Letters Patent and making part of the same.

TO ALL WHOM IT MAY CONCERN:

Be it known that I, HENRY O. LOTHROP, of Milford, in the county of Worcester, and State of Massachusetts, have invented certain new and useful Improvements in Steam-Engines; and do hereby declare the following to be a full, clear, and exact description thereof, reference being had to the accompanying drawings, and in which—

Figure 7 is a top view, and

Figure 8 is a vertical section of that part of a steam-engine to which my present improvements are applied.

The arrangement of the cylinder and valve-apparatus of the engine represented in the drawings, is substantially that for which I have recently applied for and obtained Letters Patent of the United States, and need not therefore be described.

My present invention has relation to the special mode of connecting the three cylinder-pistons to the driving-shaft of the engine, the object of this arrangement being to simplify the construction and to lessen the cost of the engine. That this object is fully accomplished, will be readily understood by reference to the drawings.

As shown in the said figs. 7 and 8, the two end pistons A^1 A^3 are bolted securely together, and connected to the cranks a^4 a^6 of the driving-shaft A^2 , by two connecting-rods b^4 b^6 .

The piston-rod c^4 of the central piston B^2 slides freely through the piston A^3 , and is connected to a head, d^4 , sliding in guides or ways e^4 e^6 , disposed centrally between the connecting-rods b^4 b^6 . This head d^4 being connected with the central cranks f^4 of the driving-shaft by a connecting-rod, g^4 , this latter crank f^4 being in a plane directly opposite to the cranks a^4 a^6 , before mentioned.

It will be seen, without further explanation, that this arrangement of the pistons and above-described mechanism, by which they are connected with the driving-shaft, dispenses with many of the parts heretofore employed, and thus reduces the cost and simplifies the construction of the engine, which at the same time is still maintained in condition to operate with results equally good as those described in the patents hereinbefore referred to.

Having described my invention, and the manner in which the same is or may be carried into effect, what I claim, and desire to secure by Letters Patent, is—

The arrangement, with the rods b^4 connecting the pistons A^1 A^3 with their crank or driving-shaft, of the rods c^4 g^4 , and sliding cross-head e^4 , connecting the piston B^2 with said shaft, substantially as herein shown and described.
